UNITED STATES PATENT OFFICE.

ED B. RAYMOND AND CLAUDE R. WATSON, OF WICHITA, KANSAS.

FLUID-HYDROCARBON BURNER.

1,039,194.

Specification of Letters Patent. Patented Sept. 24, 1912.

Application filed November 24, 1911. Serial No. 662,234.

To all whom it may concern:

Be it known that we, ED B. RAYMOND and CLAUDE R. WATSON, citizens of the United States, residing at Wichita, in the county 5 of Sedgwick, State of Kansas, have invented a new and useful Fluid-Hydrocarbon Burner, of which the following is a specification.

The present invention relates to improvements in fluid hydro-carbon burners, the primary object of the invention being the provision of a fuel oil burner adapted to be disposed upon the grate of an ordinary range, cooking stove, heating stove, hot air 10 furnace and hot water and steam heating boilers, the said burner being so constructed as to be placed upon the upper surface of the grate within the fire box of the apparatus, the remaining portion of the grate 15 surface rounding the same being sealed against the admission of air through the draft doors and chimney so that the flow of air is directed through the fluid hydro-carbon burner to be properly mixed with the vapors 20 of the oil to produce an intensely hot and fully consumed gas.

A further object of the present invention is the provision of a fluid hydro-carbon burner composed of a few number of separable parts, the same being preferably made 30 circular in form so that the fluid hydro-carbon is admitted concentrically from below to a fluid dispensing disk which is provided with a plurality of channels upon the upper 35 face thereof and a series of concentric slots therethrough whereby the current of air entering from below will properly commingle with the vapors generated by the diffused oil or fluid hydro-carbon upon the upper 40 surface of the fluid dispensing disk, the peculiar shape of spreader being disposed above and concentrically of the fluid dispensing disk to direct the flame caused by the ignition of the hydro-carbon gas emitting 45 from the burner in the form of a circle so that the entire fire box will be properly heated.

A still further object of the present invention is the provision of a fluid hydro-carbon 50 burner adapted to be placed upon the upper surface of grates of ordinary stoves, and provided with an annular air inlet channel with centrally disposed fluid dispensing disk and drip pan, with a truncated conical outer 55 casing fitting above and around the drip pan and fluid dispensing disk so as to confine the

current of air entering from the bottom through the annular channel and cause the same to be directed to commingle with the gas vapors generated in the fluid dispensing disk, a conical spreader being invertibly disposed with its apex above and concentrically of the fluid dispensing disk so as to guide the fluid hydro-carbon properly to the fluid dispensing disk and at the same time provide a means for diffusing the flame to produce a circular flame at the upper rim of the mixing chamber of the burner.

With the foregoing and other objects in view which will appear as the description 60 proceeds, the invention resides in the combination and arrangement of parts and in the details of construction hereinafter described and claimed, it being understood that changes in the precise embodiment of 65 invention herein disclosed can be made within the scope of what is claimed without departing from the spirit of the invention.

In the drawings—Figure 1 is a vertical sectional view through the fluid hydro- 70 carbon burner showing the same operably connected to the grate of a stove. Fig. 2 is a section taken on line 2—2 of Fig. 1. Fig. 3 is a section taken on line 3—3 of Fig. 1. Fig. 4 is a detail perspective view 75 of the reduced end of the flame spreader.

Referring to the drawings, the numeral 1 designates the grate bars of any form of stove, having mounted thereon a sheet metal plate 2 carrying the lower ring 3 of the 80 burner, whose flange 4 is annularly disposed to rest upon the sheet metal plate 2 and be held in place thereon by means of the fire clay 5, said sheet metal plate 2 and fire clay 5 sealing the remainder of the grate so as 85 to prevent the passage of air from the usual air admitting dampers through the fire box or grate of the stove to the chimney, except through the opening 6 cut out of the metal plate 2 as indicated in Fig. 1.

Cast integrally with the ring or base 3 of the burner are the spiders 7 which properly support the circular drip pan 8 provided with the upstanding rim 9, the said drip pan thereby providing an annular space or air 105 admitting channel C about said pan so that the air admitted through dampers and passing upwardly through the grate bars 1 will be admitted to the burner through the said annular passageway C so that the air will 110 be conducted within the mixing chamber 21, as will presently appear.

2
 Formed concentrically of the pan 8 is a interiorly threaded boss or sleeve 10 which has secured in the lower portion thereof the oil inlet pipe 11, which is fed from a tank, 5 (not shown), preferably by gravity, the said tank being disposed as to be slightly above the level of the fluid dispensing disk 13 which is supported concentrically by means of the tubular oil conveying pipe or support 10 12, which enters the central receptacle 14 formed in the fluid dispensing disk 13 so that the oil fed through the said pipe or tube 12 will enter the said chamber 14 and pass over the upper rim thereof into the channels 15 and 16, of the said fluid dispensing disk 13, 15 said channels being separated from each other by means of the ribs 17 which provide the air inlet slots 18 so that the air entering the passageway C will be conducted when 20 in the mixing chamber beyond the peripheral edge of the fluid dispensing disk 13 and through the slots 18 thereof, so that the gas generated by the oil held within each of the channels 15 and 16 and the recesses 19 25 will be thoroughly mixed with the currents of air passing through the grate and upwardly through the burner so that by the time the said gas has been mixed and passed over the rim of the mixing chamber 21, 30 which is supported at its shouldered portion 20 to the upper rim of the base 3, a thoroughly mixed gas is produced, so that when ignited no soot or smoke will be apparent. The mixing chamber 21 is provided as shown 35 with the igniting aperture 22 which is controlled by the pivoted closure 23 through which a flame may be inserted or projected to ignite the oil permitted to flow or drip within the drip pan 8 at the mounting of the 40 burner.

The flame spreader 24 is preferably made cone-shaped as illustrated in Fig. 1, the apex 25 thereof being specially pointed as at 26 to cause the fluid hydro-carbon or oil as it 45 enters the chamber 14 to be directed to the plurality of channels or ducts 27 so that the same will pass through the outlet a and over the upper rim of the chamber 14 and finally into the recesses 15 and 16 and radial slots 19 50 of the fluid dispensing disk 13. It will thus be seen that this burner comprises but three separable parts, the base 3 which carries the drip pan 8 and the vertical stem 12 which supports the fluid dispensing disk 13 being 55 one part, while the mixing chamber in reality being a tapered open ring 21, being another part, while the spreader 24 is the third, thus providing an exceedingly simple and inexpensive burner and one which may 60 be readily removed to be cleaned, that is, when it is desired to clean the same the spreader 24 is removed first, and with a brush may be cleaned of the soot or any other products of combustion collecting 65 thereon, the removal of the spreader 24 per-

mitting the mixing chamber or ring 21 to be moved upwardly and from about the fluid dispensing disk 13, thus exposing the said fluid dispensing disk and drip pan so that the same may be brushed and properly 70 cleaned.

When it is desired to light the burner, it is simply necessary to open a valve, not shown, so that the flow of oil or fluid hydro-carbon through the pipe 11 may be controlled to a nicety according to the heat desired to be generated. This action permits the oil to flow into the channels of the fluid dispensing disk 13 and to drip therefrom into the drip pan 8. When the lower surface of the drip pan 8 has been covered with the oil, the closure 23 is moved to permit the introduction of a flame through the aperture 22 to ignite the oil both in the drip pan 8 and in the channels of the fluid dispensing disk 13. When the oil has sufficiently burned to produce the desired heating of the parts of the burner, the valve is again turned on and the oil admitted through the stem 12 into the channels of the fluid dispensing disk 13 will become ignited, the regulation of the flow of air through the passageway C into the mixing chamber and around the fluid dispensing disk 13 being controlled entirely through 90 the means of the regular stove dampers, so that the flame produced and diffused from the upper rim of the mixing chamber 21 will be according to the amount of air and oil supplied. By this means it is evident 100 that the flame may be readily controlled to attain heat for various purposes when cooking and when used in heating stoves or furnaces, the same may be controlled to have a low flame in mild weather and a high flame 105 in cold weather.

The burner is preferably made of cast iron, and as illustrated in Fig. 1, is readily placed in operable position by any mechanic, it simply being essential that the grate be 110 sealed entirely except at the opening 6, as indicated in Fig. 1, so that the air is directed entirely within the mixing chamber 21 of the burner to be properly mixed with the vapors due to the rising temperature effect upon the hydro-carbon fluid or oil within the grooves or recesses of the fluid dispensing disk 13.

What is claimed is:

1. A fluid hydro-carbon burner, having 120 an annular base, a concentric drip pan carried thereby and providing therewith a plurality of peripherally disposed air admitting ports, a concentrically disposed oil feed pipe projecting upwardly from the drip pan, a fluid dispensing disk provided with a concentric chamber, the upper rim of which terminates above the upper surface of the disk and in communication with the upper end of the oil feed pipe, a tapering ring 125
- 130

mounted upon the base and surrounding the fluid dispensing disk to form a mixing chamber, and a conical flame spreader invertedly disposed with the apex thereof concentric of the chamber of the fluid dispensing disk, the surface of the spreader adjacent the rim of the chamber of the fluid dispensing disk being provided with a plurality of oil passages to conduct the oil to 10 the fluid dispensing disk.

2. A fluid hydro-carbon burner, having an annular base provided with an outwardly projecting flange, a drip pan carried by the base within the same and providing an annular air admitting channel therearound, a concentrically disposed oil feed pipe carried by the pan and projecting upwardly therefrom, a fluid dispensing disk connected concentrically to the upper end of said pipe 20 and provided with a concentric chamber above and in communication with the upper end of said pipe, said chamber being larger in diameter than the pipe, said disk being provided with a plurality of concentric alternately disposed oil recesses and air ports, a tapering ring having the enlarged portion thereof fitting upon the base and forming a mixing chamber about the fluid dispensing disk, and a flame spreader 30 removably mounted in the concentric chamber of the fluid dispensing disk and projecting above the fluid dispensing disk and mixing chamber.

3. A fluid hydro-carbon burner, having an annular base provided with an outwardly projecting flange, a drip pan carried by the base within the same and providing an annular air admitting channel therearound, a concentrically disposed oil pipe carried by 40 the pan and projecting upwardly therefrom, a fluid dispensing disk connected concentrically to the upper end of said pipe and provided with a concentric chamber in communication with the upper end of said pipe, said chamber having an upper open end of

larger diameter than the pipe, said disk being provided with a plurality of concentric alternately disposed oil receptacles and air ports, a tapering ring having the enlarged portion thereof fitting upon the base and 50 forming a mixing chamber about the disk, and a flame spreader having a tapered stem removably mounted in the concentric chamber of the disk and having its body projecting above the generator and mixing chamber. 55

4. A fluid hydro-carbon burner, having an annular base provided with an outwardly projecting flange, a drip pan carried by the base within the same and providing an annular air admitting channel therearound, a concentrically disposed oil pipe carried by the pan and projecting upwardly therefrom, a fluid dispensing disk connected concentrically to the upper end of said pipe and 60 provided with a concentric chamber in communication with the upper end of said pipe, said disk being provided with a plurality of concentric alternately disposed oil receptacles and air ports, a tapering ring having 65 the enlarged portion thereof fitting upon the base and forming a mixing chamber about the disk, and a conically shaped flame spreader provided with a plurality of grooves formed in the body portion there- 70 of adjacent the apex, the apex of the flame spreader being adapted to be projected into the chamber of the disk so that the grooves thereof form a plurality of oil directing radially disposed ducts leading outwardly 75 above the disk. 80

In testimony that we claim the foregoing as our own, we have hereto affixed our signatures in the presence of two witnesses.
